UNITED STATES PATENT OFFICE.

JACOB MUELLER, OF CHICAGO, ILLINOIS, ASSIGNOR TO MUELLER BROTHERS ART AND MANUFACTURING COMPANY, OF CHICAGO, ILLINOIS, A CORPORATION OF ILLINOIS.

MACHINE FOR MAKING PICTURE-FRAMES.

941,331.

Specification of Letters Patent. Patented Nov. 23, 1909.

Application filed December 2, 1907. Serial No. 404,328.

To all whom it may concern:

Be it known that I, JACOB MUELLER, a citizen of the United States, residing in the city of Chicago, in the county of Cook and State 5 of Illinois, have invented certain new and useful Improvements in Machines for Making Picture-Frames, of which the following is a full, clear, and exact description.

My invention relates to certain new and 10 useful improvements in machines for making picture frames.

The invention designs to provide an improved machine for wrapping or coiling a series of thin glued sheets of wood, card- 15 board or the like around a mandrel of suitable size and shape to give the finished frame the desired form.

One form of frame which this machine produces is illustrated in an application for 20 Letters Patent of the United States filed by me on the 11th day of March, 1907, and given the Serial No. 361,826, but it is to be understood that the invention is not to be limited to a machine for making this particular frame alone, as it can be used for 25 making round or elliptical frames which are composed of one strip wrapped or coiled upon and around itself.

The invention is illustrated by means of 30 drawings furnished herewith which show one form of embodiment of the invention, in which—

Figure 1 is a central longitudinal section of the machine. Fig. 2 is a plan view 35 thereof. Fig. 3 is a diagrammatical view showing the manner of wrapping the sheets about the mandrel. Fig. 4 is a plan view of a plurality of sheets or strips from which the frames are made. Fig. 5 is an end view 40 of the machine. Fig. 6 is a side view of the front end. Fig. 7 is a detail vertical section taken on line 7—7, Fig. 5. Fig. 8 is a detail horizontal section taken on line 45 8—8, Fig. 7. Fig. 9 is a perspective view of a mandrel or block upon which the frames are built up. Fig. 10 is a perspective view of a completed frame structure. Fig. 11 is a face view of a single frame and Fig. 12 is an edge view thereof.

50 Referring to the drawings, 1 is a frame of substantial construction comprising uprights or posts 2, longitudinal members 3 and cross member 4. Upon the front posts are supported several boxes 5, 6, 7, in which are journaled shafts 8, 9, 10, that bear roll-

ers or pulleys 11, 12, 13. The front uprights or posts 2 are formed with guideways 14 (see Figs. 7 and 8) in their upper ends, in which guideways are slidably mounted bearing blocks 15. The bearing blocks 15 are raised and lowered by screws 16, which are mounted in brackets 17, and threaded in the bearing blocks. Rotation of the screws is effected by gearing which as shown consists in gears 18 upon the screws which, gears 65 mesh with gears 19, that are mounted upon a shaft 20, which is journaled in bearings 21 secured upon the cross bar 4. Two drive pulleys 23, 24, are loosely mounted on the shaft 20, and are adapted to be coupled thereto by means of a clutch mechanism 25 which is keyed or otherwise slidably connected with the shaft. The pulleys are driven in opposite directions by straight and twisted belts 26, 27, so that by throwing the clutch into operative connection with one of the pulleys 23, 24, the screws 16 will be caused to rotate in one direction thereby raising the bearing blocks 15, and by throwing the clutch into operative connection with the other pulley, the reverse movement of the bearing blocks will be had. The clutch is operated by a lever 28, which is connected to a hand lever 29 by a link 30.

A shaft 31 is journaled in the bearing blocks 15, and carries a roller or pulley 32. This pulley is the drive pulley of the series of pulleys and receives its movement from the shaft 9, through the medium of pinions 32, 33, 34. The pinions 32, 33, are fast upon the shafts 31, 9, respectively and the pinion 34 is journaled in an arm 35 which is fulcrumed upon the shaft 9 and arranged to be swung upon said shaft as a center to bring the pinion 34 into mesh with the pinion 32 or to throw it out of gear therewith. A catch 36, is arranged to hold the pinions in operative position. This arrangement is provided to accommodate the vertically movable shaft 31, so as to connect and disconnect it mechanically with the shaft 9. A drive pulley 22 is loosely mounted upon the shaft 9, and is arranged to be operatively connected therewith by a clutch 37 which is keyed or otherwise slidably connected 105 with the shaft 9. The clutch is actuated by a lever 38, which is connected to a hand lever 39 by a link 40. The shaft 9, preferably turns loosely within the pulley 12 and if desired may consist of an entirely separate and 110

independent counter shaft for transmitting the power to the shaft 31, which is the driving shaft of the wrapping mechanism. A wrapping belt 41 passes about the rollers or 5 pulleys, 11, 31, 12, 13, and about an idler or take-up pulley 42, which is secured upon a shaft 43 journaled in bearings 44, that are slidably mounted upon the frame. The bearings 44 are secured upon blocks 45 that 10 slide in guideways 46, and a cross bar 45^a connects said blocks so as to cause them to move in unison, which cross bar is connected to a weight or other tension device 47, by a cable 48 that passes over a sheave journaled 15 upon the frame 1. A tension device is thus formed which acts as a belt tightener or take-up mechanism, serving to maintain a constant tension upon the belt 41. Stops 49 may be provided to limit the backward 20 movement of the idler beyond a certain limit.

A loop or bight 41^a of the belt extends between the pulleys, 32, 12, and in said loop is supported a block or mandrel 50, around 25 which the sheets or strips are wound or coiled to form the frame structure. The mandrel, 50 is wholly independent, that is, it has no support other than the wrapping belt. The belt is drawn snugly around this 30 block during the winding process and serves not only to wrap the sheets or strips around the block but to apply sufficient pressure to the sheets or strips to press the various laps thereof tightly together to give the frame 35 its proper shape. Furthermore, the pulleys 32, 12, are set as close together as is possible, thus causing the loop to surround or engage practically the entire curved surface of the mandrel. The mandrel being unprovided 40 with any other means of support than the belt, is drawn tightly upon the pulleys 32, 12 and rolled around upon them so that the sheets or strips are not only held down upon the mandrel by the loop in the belt 45 but a rolling pressure is brought to bear upon the strip as the mandrel is rolled around upon the pulleys. The center point *a* of the mandrel travels substantially in an elliptical track as shown by the dotted lines 50 in Fig. 3 but the body of the mandrel shifts or rolls around with its curved surface bearing upon the pulleys. Of course it is to be understood that the belt lies between the mandrel and the pulleys so that the rollers bear 55 upon the mandrel through the intervening belt.

The block or mandrel is preferably made collapsible to facilitate its removal from the frame structure surrounding it and a very 60 simple expedient is shown for this purpose. The block or mandrel is in two sections 51, 52, which are connected together by two plates 53 which are hinged to the sides of the section 52 and connected to the other 65 section by pins 54 and a wingnut 55 which

is threaded upon a screw threaded pin 56. By unscrewing the wingnut the plate may be swung out of engagement with the pins and the two sections 51, 52 collapsed, to disengage them from the surrounding frame 70 structure. Fig. 4 shows a plurality of the sheets or strips A, which go to make up a frame structure, and these sheets or strips are cut into such lengths that each successive strip is enough longer than its preceding one to be wrapped around the same, after it has been wrapped or coiled around the block or mandrel. By cutting the sheets or strips into such lengths a frame structure can be made, upon which none of the sheets 80 or strips overlap themselves, but the ends of each sheet or strip abut against each other thereby making a frame of uniform cross section throughout its entire extent. This is of great importance because less work is 85 required to finish the frame and a perfectly shaped frame is formed in the first instance which requires no trimming down of its periphery to do away with the overlapping edges of the ordinary frame. I have shown 90 a work bench 60 having an inclined table 61, upon which the sheets are laid and fed into the machine. A guide 62 is provided upon this bench for directing the sheets into the machine, and a deflecting shield 63 extends 95 in between the pulleys 32, 12 to prevent the glued surface of the sheets from contacting with the belt as it passes around the roller 32.

The operation of the machine is as follows:—The block or mandrel is extended 100 to operative position and inserted into the loop or bight 41^a of the belt 41, it being understood that the pulley 32 has been previously raised to permit the ready removal or replacement of the block or mandrel. After 105 the mandrel has been inserted into the loop, the hand lever 29 is shifted to throw the clutch 25 into operative connection with the pulley 23 whereupon the bearing blocks 15 will be lowered carrying the shaft 31, pulley 110 32, and belt 41 down toward the pulley 12, thus practically closing the loop around the block against the tension afforded by the weight 47, but leaving an opening between the pulleys 32, 12, through which the sheets 115 may be inserted. The pinion 34 is then swung into operative position to connect the pinions 32, 33 and the hand lever 39 shifted to throw the shaft 9 into operative connection with the pulley 22. The rotation of 120 the pulley 32 draws the belt 41, around the block or mandrel 50 and through the machine, causing the block to roll around, under the influence of the moving belt. The tension upon the belt afforded by the weight, 125 serves to draw the block upon the pulleys 32, 12, the belt 41, however, being interposed between the block and pulleys. The shortest of the sheets or strips is then fed in between the block and the lower half of the loop, and 130

as soon as it is gripped between the block and belt, it will immediately be drawn in between the block and loop and thus held snugly upon the block regardless of the shape of the block. Glue is then applied to the remaining sheets or strips and they are fed upon the first one in succession beginning with the smallest and continuing until the longest one is wrapped or coiled upon the others. Care should be taken to see that the meeting edges of the strips break joint so that the meeting edges may be distributed around the frame structure thus formed. After all of the sheets or strips forming one frame structure have been wrapped upon the block the machine is stopped, the pulley 32 raised and the block removed from the loop. The block is then collapsed within the surrounding frame structure and the latter removed. Afterward this frame structure is sawed up into frames A', having a thickness from front to back of about half an inch, and the frames are then trimmed and finished as usual.

25 It is perfectly obvious that the contour of the block or mandrel 50 may be altered to produce frames of other shapes, that is, the ellipse may be longer or flatter as desired, and in fact the contour of the block may be 30 a perfect circle so that a round frame may be made thereon. Furthermore, the size of the blocks may be varied, thus providing means for making various sized and shaped frames. One advantage in this machine is 35 that blocks of different sizes and shapes may be employed without any fine adjustment of any of the other parts of the machine, as the take-up mechanism causes the wrapping belt to accommodate itself to the various 40 sized and shaped blocks. Furthermore, by rolling the mandrel upon the pulleys 32, 12, the sheets are rolled down upon each other and perfect contact and union between them is effected.

45 While I have shown this invention in its simplest form, I do not wish to be understood as intending to limit myself to the specific form shown and described as it will

be understood that it is capable of modifications. I do not therefore desire to be limited 50 in the interpretation of the following claims except as may be necessitated by the state of the prior art.

I claim as new and desire to secure by Letters Patent:—

1. In a device of the class described, the combination with a frame having two vertical side members, of a wholly independent mandrel, wrapping means including a movable belt running between said side members and having a loop extending partially around the mandrel and forming the sole support therefor, two pulleys for maintaining the loop upon the mandrel, and means for adjusting said pulleys toward or away 65 from each other to such a range as to permit the insertion of the mandrel between the pulleys into the loop of the belt.

2. In a device of the class described, the combination of a mandrel, a wrapping belt 70 having a loop extending around said mandrel, pulleys between which the belt is passed to form the loop, suitably guided bearing blocks for one of said pulleys, and means for raising and lowering said bearing 75 blocks in unison.

3. In a device of the class described, the combination of a mandrel, a wrapping belt having a loop extending around the mandrel, pulleys between which the belt is 80 threaded to form the loop, suitably guided bearing blocks for one of said pulleys, screws threaded in said bearing blocks, pinions mounted upon said screws, a cross shaft, pinions mounted upon said cross shaft and 85 meshing with said first named pinions, and means for rotating said cross shaft in either direction.

In witness whereof, I have executed the above application for Letters Patent at Chicago, Illinois, this 30th day of November, 90 A. D. 1907.

JACOB MUELLER.
